(57) **CLAIM**

The ornamental design for a confocal microscope, as shown and described.

DESCRIPTION

FIG. 1 is a perspective view looking downwardly at the left side of a confocal microscope in accordance with our design;

FIG. 2 is a left side view thereof;

FIG. 3 is a right side view thereof;

FIG. 4 is a front elevation view thereof;

FIG. 5 is a rear elevation view thereof;

FIG. 6 is a top view thereof;

FIG. 7 is a bottom view thereof;

FIG. 8 is a perspective view looking at the right side thereof in which the imaging head of the confocal microscope is shown tilted from its position shown in FIGS. 1-6; and,

FIG. 9 is a perspective view looking at the rear elevation thereof in which the imaging head of the confocal microscope is also shown tilted from its position shown in FIGS. 1-6.

1 Claim, 9 Drawing Sheets
